UNITED STATES PATENT OFFICE

2,663,979

SANDING BLOCK

Gerardo Sierchio, Pequannock, N. J.

Application March 24, 1952, Serial No. 278,146

5 Claims. (Cl. 51—187)

1

This invention relates to new and useful improvements in sanding blocks and the primary object of the present invention is to provide a sanding block so constructed as to permit the same to be grasped close to its center of gravity, whereby the same may be used and manipulated in a convenient manner.

Another important object of the present invention is to provide a sanding block having novel and improved means for removably securing a sanding sheet thereto in a convenient manner so that the sheet may be removed readily and replaced by a new sheet.

A further object of the present invention is to provide a surface treating member including a long handle and novel and improved means for removably attaching the handle to the member so that the member may be held into contact with a surface by a user disposed close to or remote from the surface.

A still further aim of the present invention is to provide a surface treating member that is simple and practical in construction, strong and reliable in use, neat and attractive in appearance, small and compact in structure, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, in which:

Figure 1 is a perspective view of the present invention and showing the handle removed therefrom;

Figure 2 is a longitudinal vertical sectional view taken substantially through the center of Figure 1 and with the handle applied;

Figure 3 is a plan view of the invention showing the hand grip pivoted to clear the ends of the base member, whereby the abrasive sheet may be applied to or removed from the base member; and

Figure 4 is a vertical sectional view taken substantially on the plane of section line 4—4 of Figure 3.

Referring now to the drawings in detail wherein for the purpose of illustration, there is disclosed a preferred embodiment of the present invention, the numeral 10 represents an elongated substantially rectangular base member of any suitable light-weight material, having a central frusto-conical recess or well 12 in its upper face and a central aperture 14 whose lower end is formed with a countersink 16.

2

A screw 18 extends upwardly through the aperture 14 and its head 20 is positioned in the countersink 16. The screw 18 receivably engages a nut 22 that forces a washer 24, about the screw, downwardly against the bottom wall of recess 12 to clampingly secure the screw to the base member 10.

A flat substantially H-shaped hand grip 26 overlies the base member 10 and includes a pair 10 of parallel portions 28 and 30 that are joined by a cross portion 32. Gripping ribs 34 and 36 are provided on the undersurfaces of the portions 28 and 30 and overlie the ends of the base member 10. The side edges 38 of the cross portion 15 32 are convex and curve downwardly toward the recess 12 and the center of portion 32 is formed with an aperture 40 that receives the screw 18.

A central recess 42 is provided in the upper face 20 of the hand gripping portion 32 about the aperture 40 and receives a wing nut 44 threaded on the upper end of the screw 18.

Means is provided for removably securing a handle 46 to the hand grip 26. This means comprises a V-shaped wire attaching element 48 having a loop 50 formed at its apex that enters a slot in the outer end of the handle 46. A fastener 52 extends through the handle 46 and the loop 50 to removably secure the handle to the element 48.

The hand grip 26 is formed with a pair of downwardly diverging openings or apertures 54 in which metallic sleeves 56 are fitted. The sleeves 56 yieldingly receive the ends of element 48.

In practical use of the present invention, the nut 44 is backed up and the hand grip 26 swung 35 to the position shown in Figure 3, whereby the ends of an abrasive sheet or surface treating member M may be folded over the ends of the base member 10.

Hand grip 26 is then swung over the base member 40 so that the ribs 34, 36 engage the ends of the sheet M. Then the nut 44 is tightened to clamp the ends of sheet M against the upper face of base member 10.

A user will grasp portion 32 with one hand and the hand will enter recess 12 and will extend over the wing nut 44 and the upper end of screw 18, to position the user's hand close to the sheet M, thereby facilitating convenient manipulation of the base member.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A sanding block comprising an elongated rigid base member having upper and lower faces, said base member also having a central recess in its upper face, a substantially H-shaped hand grip overlying the base member and including a pair of parallel end portions of a length substantially equal to the width of the base member and a cross portion joining intermediate parts of said parallel end portions and extending immediately above the recess, whereby a user's hand disposed about the cross portion will enter the recess, and a combined pivot and fastener extending centrally through the base member and the cross portion.

2. A sanding block comprising an elongated rigid base member having upper and lower faces, said base member also having a central recess in its upper face, a substantially H-shaped hand grip overlying the base member and including a pair of parallel end bars and a cross-bar joining said parallel end bars and extending immediately above the recess, whereby a user's hand disposed about the cross-bar will enter the recess, a screw fixed to the center of the base member and extending upwardly from the recess, said cross-bar of said hand grip having a central aperture receiving the screw, and a nut threaded on the screw engaging the cross-bar.

3. A sanding block comprising an elongated rigid base member having upper and lower faces, said base member also having a central recess in its upper face, a substantially H-shaped hand grip overlying the base member and including a pair of parallel end bars and a cross-bar joining said end bars and extending immediately above the recess, whereby a user's hand disposed

about the cross-bar will enter the recess, gripping ribs on the parallel portions at the underside of the hand grip, and a combined fastener and pivot securing the cross-bar to the center of the base member and clamping the ribs against the upper face of said base member.

4. A sanding block comprising an elongated rigid base member having upper and lower faces, said base member also having a central recess in its upper face, a substantially H-shaped hand grip overlying the base member and including a pair of parallel portions and a cross portion joining said parallel portions and extending immediately above the recess, whereby a user's hand disposed about the cross portion will enter the recess, said central portion having downwardly curved edges extending toward the recess, a screw having a lower end fixed to the center of the base member and extending upwardly from the recess, said central portion having a central aperture accommodating the screw and a countersink at the upper end of the aperture, and a wing nut threaded on the screw and received in the countersink.

5. The combination of claim 1, and a substantially V-shaped wire attaching element having a central loop, said hand grip having a pair of vertically inclined apertures, sleeves fitted in the apertures, the ends of said element being positioned in the sleeves, and a handle attached to the loop.

GERARDO SIERCHIO.
